UNITED STATES PATENT OFFICE

JOSEPH H. COHEN, OF BRIDGEPORT, CONNECTICUT

DESIGN FOR A COMBINED ASH RECEIVER AND CIGAR LIGHTER

Application filed September 8, 1931. Serial No. 41,043. Term of patent 14 years.

To all whom it may concern:

Be it known that I, JOSEPH H. COHEN, a citizen of the United States, residing at Bridgeport, in the county of Fairfield and State of Connecticut, have invented a new, original, and ornamental Design for a Combined Ash Receiver and Cigar Lighter, of which the following is a specification, reference being had to the accompanying drawing, forming part thereof.

Figure 1 is a top plan view of the combined ash receiver and cigar lighter showing my new design.

Fig. 2 is a front elevation of the same.
Fig. 3 is a side elevation of the same.

The dominant feature of my design is the ornamented panel at the top portion of the device.

I claim:

The ornamental design for a combined ash receiver and cigar lighter, as shown and described.

JOSEPH H. COHEN.
